DESIGN FOR A COMBINED BRUSH AND RAZOR HOLDER

Elmer J. Jones, San Francisco, Calif.

Application October 26, 1937, Serial No. 72,433

Term of patent 14 years

To all whom it may concern:

Be it known that I, Elmer J. Jones, a citizen of the United States of America, residing at San Francisco, in the county of San Francisco and State of California, have invented a new, original, and ornamental Design for a Combined Brush and Razor Holder, of which the following is a specification, reference being had to the accompanying drawing forming a part thereof.

Fig. 1 is a top plan view of a combined brush and razor holder, showing my new design;

Fig. 2 is a front elevation thereof; and

Fig. 3 is a side view thereof.

I claim:

The ornamental design for a combined brush and razor holder, substantially as shown.

ELMER J. JONES.
